UNITED STATES PATENT OFFICE.

JOSEPH COFFMAN, OF LIBERTY, INDIANA.

GRAIN-CARRIER.

SPECIFICATION forming part of Letters Patent No. 756,938, dated April 12, 1904.

Application filed August 1, 1903. Serial No. 107,844. (No model.)

To all whom it may concern:

Be it known that I, JOSEPH COFFMAN, a citizen of the United States, residing at Liberty, Indiana, have invented a new and useful Improvement in Grain-Carriers, of which the following is a specification.

My invention relates to grain-carriers of that class adapted to use on harvesting-machines and elsewhere; and the objects of my improvement are to dispense with the ordinary canvas carriers and to provide carriers which are not affected by exposure to the weather; to provide carriers which are continuous throughout the platform, elevator, and deck; to provide fingers on endless chains which are hinged thereon and adapted to be turned laterally to horizontal or vertical positions; to provide means to move the fingers into vertical operative position; to provide means to fold the fingers horizontally after the load is discharged for the purpose of utilizing a thinner platform, and to provide a platform that is substantially solid. These objects are attained in the following-described manner, as illustrated in the accompanying drawings, in which—

Figure 1 is a transverse section of the platform, elevator, and deck on the line of one of the endless-chain carriers; Fig. 2, a longitudinal section of portions of the platform on the line $\alpha\alpha$; Fig. 3, an elevation of portions of the grain end of the platform, showing the slanting groove adapted to lift the chain-fingers from folded to operative position; Fig. 4, an elevation of portions of the delivery end of the deck, showing the slanting groove adapted to fold the fingers to horizontal positions; Fig. 5, a plan, and Fig. 6 a cross-section of a chain provided with a laterally-folding finger.

In the drawings, 7 represents the platform of a harvesting-machine, 8 the elevator, inclined upwardly therefrom, and 9 the deck, declined at right angles from the elevator, all being securely connected together to form a single structure. A series of endless-chain grooves 11 are formed parallel with each other around said structure and just beneath its upper and above its under surface. Open finger-grooves 12, formed vertically in the upper

surface of the structure, communicate with one edge of the respective grooves 11 and form right angles in cross-section thereto. Said finger-grooves are extended throughout the bottom portion of said structure and 55 form horizontal lateral extensions 13 of said chain-grooves 11, as shown in Fig. 2. Said vertical and horizontal grooves 12 and 13 communicate with each other at the grain end of the platform and at the discharge end of the 60 deck through quarter-turn grooves 14 and 15, respectively, as shown in Figs. 3 and 4. Endless sprocket-chains 16 are mounted in the respective chain-grooves and driven therethrough in the direction indicated by the arrows by means of corresponding sprocket-wheels 17, mounted on driving-shaft 18. Said shaft is journaled in the outer portion of the angle formed by the elevator with the platform. Idle sprocket wheels or rollers 21, 22, 70 23, and 24, serve to carry the chains around corresponding angles to avoid excessive friction. Preferably at regular intervals in the length of each chain a finger 25 is hinged to one side of a link, as shown in Figs. 5 and 6. 75 The side of the link forms the pintle of the hinge, and the hinge portion 26 of the finger is preferably formed with a lug 27 on one or both ends to engage with a cross-bar of the link and limit the lateral swing or movement 80 of the finger from exceeding the vertical or horizontal positions. Shield 28 is mounted over the elevator, and butter 29 is secured to the deck, as in ordinary forms of construction. The portion of the chain-grooves 11 in the 85 deck decline at an angle to its surface, and the open finger-grooves 12 formed therein become deeper toward its discharge end, whereby the fingers are withdrawn therein and disengaged from the grain just before its delivery to the binder mechanism. (Not shown.)

In operation the cut grain falls on the platform and is engaged by and carried laterally by the fingers, which project vertically through the finger-grooves and above the surface of 95 the platform. The movement of the grain is continued under the shield up the surface of the elevator and toward the discharge end of the deck. The gradual deepening of the finger-grooves in the surface of the deck causes 100

the fingers to be withdrawn therein and disengaged from the grain to prevent any of the grain becoming entangled with the fingers and carried beyond the point of delivery. After 5 the fingers are withdrawn beneath the grain they enter the quarter-turn of the groove, whereby they are folded from the vertical to the horizontal position to occupy less vertical space and avoid contact with all external obstacles in their return under the structure to the grain end of the platform, where they are caused to resume the vertical position by their 10 passage through the quarter-turn portion of the grooves formed at this point in the platform.

This form of construction permits the platform and other parts of the structure to be made solid with the exception of the grooves 15 therein and to be as thin as may be necessary to cut close to the ground and receive the grain properly thereon, and both the upper and lower surfaces of the structure outside of the grooves may be formed of sheet-metal securely fastened thereon, as shown at 31 in Fig. 2.

Having fully described my improvement, what I claim as my invention, and desire to secure by Letters Patent of the United States, 20 is—

30 1. In a grain-carrier, the combination with an integral structure consisting of a horizontal platform, an elevator inclined upwardly therefrom and a deck declining at right angles from

the elevator, said structure being formed with L-shaped open grooves in its upper surface 35 and with horizontal grooves in the under surface of the platform portion and communicating by quarter-turns with said L-shaped grooves, the grooves in the deck portion being gradually deepened toward its discharge 40 end, of endless chains movable in the corresponding said grooves, laterally-movable fingers mounted at intervals thereon, driving sprocket-wheels for the chains mounted at the external angle between the platform and the 45 elevator, and idle antifriction-rollers mounted respectively at the grain end of the platform, the discharge end of the deck and in the external and internal angles between the elevator and deck, for the purpose set forth.

2. In a grain-carrier the combination of a deck formed integral with an elevator and a platform, said deck having open L-shaped grooves in its upper surface, said grooves being gradually deepened and terminating in 55 quarter-turns around the discharge end of the deck, of endless chains movable in said respective grooves, laterally-movable fingers mounted at intervals on the chains, and driving-wheels for the chains mounted at the junction 60 of the platform with the elevator, substantially as specified and for the purpose set forth.

JOSEPH COFFMAN.
